CHRISTIAN PFEFFER, OF BUFFALO, NEW YORK.

Design No. 3,388, dated February 23, 1869.

DESIGN FOR A PICTURE-FRAME

The Schedule referred to in these Letters Patent and making part of the same.

To all whom it may concern:

Be it known that I, CHRISTIAN PFEFFER, of the city of Buffalo, in the county of Erie, in the State of New York, have originated and designed a new Moulding for Picture-Frames, of which the following is a full, clear, and exact description, reference being had to the accompanying drawings, making part of this specification.

Figure 1 is a plan of the picture-frame.

Figure 2 is a cross-section of the designed ornamented moulding, of which—

A is a gold border, secured to the outer clasp by means of a groove, as seen in fig. 2. Said border is left loose. It is not glued into the groove, as hitherto done by others.

B is the outside clasp of the designed ornamented

picture-frame moulding. It is neatly ornamented by corrugation. In its cross-section it shows a round or curved form. It does therefore look neat and finished-like when seen in any direction. A peculiarity of the corrugation consists in having each of the grooves in its cross-section show a uniformity around the whole clasp.

Having thus fully explained my invention, What I desire to secure by Letters Patent, is— The design of a picture-frame moulding, as shown and specified in fig. 2.

CHRISTIAN PFEFFER.
